DESIGN FOR A DISPENSER FOR INSECTICIDES OR THE LIKE

Samuel McDuffee, Glendale, Calif.

Application July 3, 1946, Serial No. 131,313

Term of patent 14 years

(Cl. D31—3)

To all whom it may concern:

Be it known that I, Samuel McDuffee, a citizen of the United States, residing at Glendale, Los Angeles County, California, have invented a new, original, and ornamental Design for a Dispenser for Insecticide or the like, of which the following is a specification, reference being had to the accompanying drawings, forming a part thereof.

Fig. 1 is a side elevational view of a dispenser for insecticide or the like embodying my new design;

Fig. 2 is a front elevational view;

Fig. 3 is a rear elevational view; and

Fig. 4 is a top plan view thereof.

I claim:

The ornamental design for a dispenser for insecticides or the like, as shown.

SAMUEL McDUFFEE.
